UNITED STATES PATENT OFFICE.

JOSEPH E. SCHMID, OF BUFFALO, ASSIGNOR OF ONE-HALF TO EMIL LAASS,
OF SYRACUSE, NEW YORK.

DOOR-HANGER.

SPECIFICATION forming part of Letters Patent No. 293,598, dated February 12, 1884.

Application filed November 7, 1882. (No model.)

To all whom it may concern:

Be it known that I, JOSEPH E. SCHMID, of the city of Buffalo, in the county of Erie and State of New York, have invented a new and 5 useful Improvement in Door-Hangers, of which the following is a specification.

This invention relates to an improvement in that class of door-hangers which are employed for supporting sliding doors from the 10 top, and which consist of rollers or wheels attached to the upper edge of the door in suitable bearings and running on horizontal rails.

The object of my invention is to so construct the hanger that it can be easily applied 15 to the door and adjusted, and that it is simple in construction.

My invention consists of the particular construction of the hanger, which will be hereinafter fully described, and pointed out in the 20 claim:

In the accompanying drawings, consisting of two sheets, Figure 1 is a section of one of my improved door-hangers. Fig. 2 is an elevation at right angles to Fig. 1. Fig. 3 is a perspective view of the hanger with the wheels removed. Figs. 4 and 5 represent modified constructions of the adjustable hanger-frame.

Like letters of reference refer to like parts in the several figures.

30 A represents the upper portion of a sliding door, and B B the horizontal rails, arranged above the door in the usual manner.

C C represent the wheels or rollers of the hanger, which are secured to a shaft, c, at the 35 proper distance apart to run upon the rails B B.

D represents the frame of the hanger, which is secured with its lower end to the upper side of the door A, and provided at its upper end 40 with a hook or half-bearing, d, which engages over the shaft c between the rollers C C. The frame D is located between the rails B B, and composed of a plate, f, which is secured to the upper side of the door by screws f', and an up- 45 wardly-extending curved arm, g, which connects the plate f with the half-bearing d.

h represents an inclined ear, which is arranged at the front end of the plate f, and i represents a screw-bolt, which extends in an

inclined position from the ear h to the upper 50 portion of the curved arm g of the frame. The screw-bolt i is provided with a notched countersunk head, j, which bears against the outer side of the ear h, and with a disk or washer, k, which bears against the inner side 55 of the ear h, and which is held in position by a pin, l. By this means the screw-bolt is prevented from moving longitudinally in the ear, but is free to turn therein. The upper threaded portion, m, of the screw-bolt i engages in 60 a threaded hole in the arm g. The frame D of the hanger is constructed of wrought-iron or other suitable metal which possesses the requisite elasticity, so that upon turning the screw-bolt i in one or the other direction the 65 bearing d can be adjusted toward or from the ear h, whereby the portion of the door A to which the bearing is attached is raised or lowered, as may be necessary to level or adjust the door. 70

n represents a roller, which is attached to the upper side of the plate f by means of a vertical screw-bolt, o, and which is somewhat larger in diameter than the width of the frame D, thereby preventing the frame from 75 coming in contact with the inner sides of the rails B B.

My improved hanger is very simple in construction, and possesses the requisite adjustability, which enables the door to be adjusted 80 and leveled, and it is attached to the door very quickly and securely.

The upper corner of the door is preferably recessed, as represented in Figs. 1 and 2, so as to permit a screw-driver to be applied to 85 the head of the screw-bolt i.

Instead of constructing the frame of elastic metal, as hereinbefore described, the arm g may be pivoted to the plate f, as represented in Figs. 4 and 5, and the screw-bolt i may be 90 applied in the same manner, as hereinbefore described, and represented in Fig. 4; or the arm g may be provided below its pivot with an extension, p, and the screw-bolt i may engage with its threaded end in a screw-threaded hole in the extension p, as represented in Fig. 5. 95

I claim as my invention—

The combination, in a door - hanger, of wheels or rollers C C, a plate, *f*, secured to the door and provided with an ear, *h*, a movable arm, *g*, provided with a bearing for the wheels 5 and connected with the plate *f*, and a bolt, *i*, connecting the fixed portion of the hanger-frame with the movable arm *g* thereof, where-

by the roller-bearing is adjusted, substantially as set forth.

JOSEPH E. SCHMID.
